LUMINOUS TUBE SIGN OR ADVERTISING DEVICE

Walter F. Koken, Webster Groves, Mo.

Application November 27, 1933, Serial No. 699,841

6 Claims. (Cl. 40—130)

This invention relates to illuminated signs or advertising devices of the type that comprise one or more luminous tubes, i. e., a closed tube or other container made of glass or the like, and 5 filled with an inert gas, such as neon gas, that will produce a colored light when subjected to the action of an electric current.

One object of my invention is to provide an illuminated sign or advertising device of the general type mentioned, that produces a novel lighting effect.

Another object is to provide a sign or advertising device of the luminous tube type, which is of such construction that when it is in operation, 15 it produces the effect of flames bursting forth from a rotating or oscillating body.

And still another object of my invention is to provide a revolving barber pole that is of novel construction and appearance.

20 I have herein illustrated my invention embodied in a revolving barber pole, but I wish it to be understood that the invention is applicable to any type or kind of illuminated sign or advertising device that is equipped with one or more so-called luminous tubes.

Figure 1 of the drawing is an elevational view of a revolving barber pole constructed in accordance with my invention, showing the rotatable member of the pole at rest or in a quiescent state.

30 Figure 2 is a top plan view of the structure shown in Figure 1.

Figure 3 is a bottom plan view of said structure; and

35 Figures 4 to 8, inclusive, illustrate various other forms of reflecting surfaces that may be used in combination with a luminous tube or tubes.

In the drawing, which illustrates a revolving barber pole embodying my invention, A designates an elongated member of non-circular shape 40 in cross section, and B and B' designate a plurality of light emitting elements that are combined with the member A. Usually the light emitting element or elements with which the apparatus is equipped, will consist of a so-called luminous tube or neon tube, and for convenience I will herein refer to the light emitting element of the apparatus as a "luminous tube". However, I wish it to be understood that my broad idea contemplates the use of any light emitting device that will produce a colored light similar to or the equivalent 50 of the colored light discharged by a glass tube filled with an inert gas through which an electric current is passed. The member A is adapted to be revolved or oscillated by any suitable mechanism (not shown), and the luminous tubes B and

B' are mounted on the exterior of said member and extend spirally or substantially spirally around said member. Any suitable means may be used to supply an electric current to the tubes so as to ionize the gas confined in the tubes, the 60 tubes B and B' herein illustrated being provided at their upper ends with electrodes 1 and 1^a, respectively, and having their lower ends joined together by an electrical conductor 1^b.

In conventional revolving barber poles of the 65 type that are equipped with neon tubes or luminous tubes, the revolving member of the pole on which the tubes are mounted is of cylindrical form and is provided with spiral stripes corresponding to the colors emitted by the gases in the 70 luminous tubes, it being the usual custom to provide said revolving member with a spiral red band surmounted by a luminous tube that will emit a red light, and a spiral blue band surmounted by a luminous tube that will emit a blue light, 75 the spiral tubes being parallel to or in concentric relation with the cylindrical outer surface of said revolving member. In my improved barber pole the member A on which the luminous tubes are mounted, is non-circular-shaped in cross 80 section, and said member A is provided with reflecting surfaces of such shape and arrangement with relation to the luminous tubes, that when said member A is in rotation, the lighting effect that is produced is that of flames bursting forth 85 from the luminous tubes and traveling lengthwise of the member A. It is immaterial whether or not the member A be provided with colored stripes in addition to the reflecting surfaces, just referred to, but I prefer to omit the colored spiral 90 stripes used in conventional barber poles and provide the member A with a brilliant exterior, all of whose portions act as reflecting surfaces for the light emitted by the luminous tubes.

The particular shape or form of the reflecting 95 surfaces on the exterior of the member A is immaterial, so long as said reflecting surfaces are located in spaced relationship with the luminous tubes and are disposed at an angle to said tubes or in otherwise than parallel relationship with 100 the same, in order that the lights projected from the tubes onto the reflecting surfaces will appear to the observer to be traveling lengthwise of the member A when said member is in rotation or oscillation. In the form of my invention shown in Figure 1 the member A is constructed in the form of a fluted column provided with vertically-disposed facets 2 arranged between concaved reflecting surfaces 3. When said member A is in 105 110

rotation, the lighting effect produced is that of flames bursting forth from the tubes B and B' and traveling lengthwise of the member A. This, it is believed, will be apparent from Figure 1, 5 wherein the reference character x designates beams of light from the luminous tubes that are projected onto the reflecting surface at the right of the center facet 2 at such an angle that they produce the effect of upwardly shooting flames, 10 and the reference character y designates beams of light from the luminous tubes that are projected onto the reflecting surface lying to the left of the center facet in such a way as to produce the effect of downwardly shooting flames.

15 The lighting effect that is obtained or produced by combining luminous tubes with reflecting surfaces of the kind described, is not only novel, but it is also exceedingly attractive. I prefer to construct member A from a shell of substantially 20 hexagonal or octagonal shape in cross section, and make the reflecting surfaces 3 between the facets 2 of said member substantially concave. This particular shape of form of the member A is not essential, however, and may be varied without 25 departing from the spirit of my invention. Thus, as shown in Figure 4, the member A may be provided with longitudinally-disposed convex surfaces 3^a separated from each other by valleys or depressions 2^a that extend longitudinally of 30 said member, or the member A may be provided on its exterior with longitudinally-disposed facets 2^b that lie between reflecting surfaces 3^b, each of which is made up of a plurality of flat surfaces disposed at an angle to each other, as shown in 35 Figure 5. In Figure 6, the reflecting surfaces 3^c between the longitudinally-disposed facets 2^c on the exterior of the member A are substantially V-shaped in cross section, and in the form shown in Figure 7 the reflecting surfaces 3^d between the longitudinally-disposed facets 2^d are almost 40 flat. Figure 8 illustrates the exterior of the revolving member A as being made up of a plurality of substantially flat reflecting surfaces 3^e disposed at an angle to each other and separated by inwardly-projecting depressions or grooves 2^e of 45 substantially V-shape in cross section.

From the foregoing it will be seen that my invention contemplates the use of reflecting surfaces of numerous shapes and forms in combination 50 with a luminous tube or tubes, and mounting said reflecting surfaces or tubes, or both the reflecting surfaces and tubes on a rotatable or oscillating member, whereby when said member is in operation, the colored light or lights emitted 55 from the luminous tube or tubes will appear to be traveling lengthwise of the longitudinal axis of the device, and hence, will produce the effect of shooting flames. As previously stated, my invention is not limited to barber poles, but is applicable to or capable of use with various kinds of signs or advertising devices of the luminous tube type. A device embodying my invention may comprise a single luminous tube or a plurality 60

of luminous tubes, and while it is preferable that the light emitting element of the device extend spirally or substantially so around a rotatable or oscillating member, this particular shape or arrangement of the light emitting element of the 80 device is not essential, so long as the light emitting means of the device is combined with reflecting surfaces which are of such shape or form that when the apparatus is in operation, the effect produced by the combination of the reflecting surfaces with the light emitting means will be that of flames or beams of light in motion. Instead of mounting the luminous tube or other light emitting means on the rotatable or oscillating member that carries the reflecting surfaces, the apparatus can be so constructed that the light emitting means is stationary and the reflecting surfaces rotate or oscillate relatively to said light emitting means.

Having thus described my invention, what I claim as new and desire to secure by Letters Patent is:

1. A sign or advertising device, comprising an elongated member adapted to move about its longitudinal axis and provided on its exterior with a plurality of longitudinally-disposed reflecting surfaces disposed at an angle to each other, and a luminous tube disposed at an angle to or in otherwise than parallel relationship with said reflecting surface.

2. A device of the kind described in claim 1, in which said luminous tube extends spirally or substantially spirally around said elongated member.

3. A sign or advertising device, comprising an elongated member adapted to move about its longitudinal axis and provided on its exterior with a plurality of longitudinally-disposed reflecting surfaces arranged in angular relationship and separated by longitudinally-disposed facets, and a luminous tube on the exterior of said member, disposed at an angle to the longitudinal axis of said member and extending across said reflecting surfaces.

4. A device of the kind described in claim 3, in which the luminous tube extends spirally or substantially spirally around said elongated member.

5. A sign or advertising device, comprising a shell of non-circular form in cross section provided with a brilliant external surface, and a luminous tube on the exterior of said shell extending spirally or substantially spirally around the same, the brilliant external surface of said shell being made up of a plurality of reflecting surfaces disposed at an angle to each other.

6. A revolving barber pole, comprising a rotatable member having a brilliant external surface made up of longitudinally-disposed reflecting surfaces of substantially concave shape in cross section separated from each other by longitudinally-disposed facets, and a luminous tube extending spirally or substantially so around said member.
